UNITED STATES PATENT OFFICE.

SVEND E. JOHANNESEN, OF PITTSBURG, PENNSYLVANIA, ASSIGNOR TO WESTINGHOUSE ELECTRIC & MANUFACTURING COMPANY, A CORPORATION OF PENNSYLVANIA.

ELECTRICAL TRANSFORMER.

No. 889,931.

Specification of Letters Patent.

Patented June 9, 1908.

Application filed March 3, 1906. Serial No. 304,114.

To all whom it may concern:

Be it known that I, SVEND E. JOHANNESEN, a citizen of the United States, and a resident of Pittsburg, in the county of Allegheny and State of Pennsylvania, have invented a new and useful Improvement in Electrical Transformers, of which the following is a specification.

My invention relates to electrical transformers and particularly to those which are known as auto-transformers.

The object of my invention is to provide such an arrangement of the parts and circuits of an auto-transformer employed in voltage regulation, that the variations in the reactance thereof with variations in the voltage adjustment may be confined within very narrow limits.

Electrical transformers that are employed in voltage regulation are generally of the type known as auto-transformers and their windings are usually sub-divided by means of leads to which circuit connections may be made. In order that the voltages of such transformers may be adjusted to suit given conditions they are frequently provided with leads, or other means are provided, whereby the point of connection of the supply circuit therewith may be varied.

When a transformer comprises a plurality of coils that are so arranged as to secure symmetrical conditions as regards magnetic leakage, the symmetry of the conditions may be disturbed by connecting the supply circuit to other points than the terminals, and it is the specific object of my invention to so arrange the coils and the circuits thereof that the voltage of the transformer may be varied without disturbing the symmetry of conditions as regards leakage, the reactance of the transformer being also maintained approximately constant or varied only between very narrow limits, with variations in the voltage.

Figure 1 of the accompanying drawing is a diagrammatic view of a transformer that is constructed and arranged in accordance with my invention and Fig. 2 is a simplified diagram of the transformer shown in Fig. 1.

A transformer 1 comprises a set of coils 2, 3, 4 and 5 that are arranged in series relation with one terminal 6 connected to a supply conductor 7 and another set of coils 8, 9, 10 and 11 that are arranged in parallel relation with one terminal connected to supply conductor 12, the members of the two sets being

symmetrically arranged with reference to each other in order that the leakage and reactance of the transformer may be very small. Each of the coils 8, 9, 10 and 11 is similarly sub-divided by means of leads 13, 14 and 15, and the points of sub-division of the coils are connected together and to stationary contact terminals 16, 17 and 18, respectively, the terminals of the coils 8, 9, 10 and 11 being connected to stationary contact terminals 19 and 20. A movable switch arm 21 may be employed as a suitable means for connecting one terminal of a motor or other translating device 22 to each or any of the stationary contact terminals 16 to 20, inclusive, and for thereby regulating the voltage applied to the motor.

In order to vary the voltage of the transformer to suit any given condition, such as that of a supply circuit that may comprise a trolley conductor 23 and a track rail 24, as indicated in Fig. 2, terminal 25 of the set of coils 2, 3, 4 and 5, is adapted to be connected to the terminals or to the points of sub-divisions of the coils 8, 9, 10 and 11. Means may be provided whereby adjustment of the connection may be effected at any time as may become desirable in a railway system, for instance, where the voltage of the supply circuit decreases as the distances from the stations, or the connection may be made permanently during the construction of the transformer, as desired. When the coils and the circuits thereof are arranged in a manner similar to what has been shown and described, the symmetry of conditions, as effecting the leakage in the transformer, will not be disturbed by variations in the total voltage of the transformer or in the voltage applied to an external circuit, and the reactance of the transformer will remain substantially constant during voltage adjustments or will vary through only a limited range. The taps whereby the coils 8, 9, 10 and 11 are sub-divided thus serve both as means whereby the voltage of an external circuit may be varied and as means whereby the total voltage of the transformer may be adjusted.

The coils 2, 3, 4 and 5 may be arranged and connected otherwise than as shown, and the number and arrangement of the coils and of the circuits of the transformer may be varied in other respects without departing from my invention.

I claim as my invention:

1. A transformer comprising a set of parallel-connected coils and another set of coils having one terminal connected to corresponding points of the parallel-connected coils, the members of the two sets of coils being alternately disposed with reference to each other.
2. The combination with a transformer comprising two sets of coils, the members of the respective sets being arranged alternately with reference to each other and those of one set being connected in parallel relation, of means for connecting one terminal of the other set of coils to corresponding points of the parallel-connected coils.
3. The combination with a transformer comprising two sets of coils, the members of the respective sets being arranged alternately with reference to each other and those of one set being connected in parallel relation, of means for connecting one terminal of the other set of coils to corresponding points of the parallel-connected coils, and means for making circuit connection to corresponding points of the parallel-connected coils.
4. A transformer comprising a set of sub-divided parallel-connected coils and a set of series-connected coils symmetrically disposed with reference to each other, one terminal of the series-connected set of coils being connected to any desired corresponding sub-divisions of all of the coils of the other set.
5. The combination with an electrical supply circuit and a translating device, of a transformer comprising a set of coils having their corresponding terminals and a plurality of corresponding intermediate points connected together in parallel and another set of coils having one terminal connected to one side of the supply circuit and another terminal adapted for connection to corresponding end and intermediate points in the coils of the other set, and means for making adjustable connection between the translating device and the parallel-connected coils.
6. The combination with a supply circuit and a translating device, of a transformer comprising a set of parallel-connected coils having intermediate taps or leads and another set of coils having one of its terminals connected to the supply circuit and its other terminal adapted for connection to corresponding end and intermediate leads from the parallel-connected coils, the coils of the two sets being symmetrically disposed, and a switch device for making adjustable connection between the translating device and the transformer leads.
7. A transformer comprising a set of sub-divided coils and another set of coils one terminal of which may be connected to the points of sub-division of the first set.
8. A transformer having a two part winding one of which is sub-divided and one terminal of the other part of which is connected to the points of sub-division of the first part.
- In testimony whereof, I have hereunto subscribed my name this 28th day of February 1906.

SVEND E. JOHANNESEN.
